DESIGN FOR A PENCIL TIP

William Cook, New York, N. Y., assignor to Eagle
Pencil Company, New York, N. Y., a corporation of Delaware

Application October 15, 1937, Serial No. 72,213

Term of patent 14 years

To all whom it may concern:

Be it known that I, William Cook, a citizen of the United States and residing at New York, New York, have invented a new, original, and ornamental Design for a Pencil Tip, of which the following is a specification, reference being had to the accompanying drawing, forming part thereof, and in which

Fig. 1 is an elevation of the pencil tip showing my new design, and

Fig. 2 is an end view of the pencil tip.

I claim:

The ornamental design for a pencil tip, substantially as shown.

WILLIAM COOK,
